CEMETERY MEMORIAL PLAQUE OR THE LIKE

Robert J. Rettman, Pittsburgh, Pa., assignor to Jas. H. Matthews & Co., Pittsburgh, Pa., a corporation of Pennsylvania

Application December 21, 1953, Serial No. 28,144

Term of patent 14 years

(Cl. D79—1)

To all whom it may concern:

Be it known that I, Robert J. Rettman, a citizen of the United States, residing in Pittsburgh, county of Allegheny, and Commonwealth of Pennsylvania, have invented a new, original, and ornamental Design for a Cemetery Memorial Plaque or the like, of which the following is a specification, reference being had to the accompanying drawing forming part thereof.

I claim:

The ornamental design for a cemetery memorial plaque or the like, substantially as shown.
